THEFT ALARM

James M. Parks, Topeka, Kans.

Application December 16, 1935, Serial No. 54,544

11 Claims. (Cl. 116—94)

This invention relates to burglar alarms of that general class operated by the power of a spring or equivalent device upon the release or severance of, or a pull on, a cord extending from the alarm device to the door, window or other movable part of the building or structure for protection, and my object is to produce an alarm device of the character indicated which can be easily and quickly applied in operative position and will be dependable in operation, and which embodies the desirable features of simplicity, strength, durability and cheapness of construction, and is of such size, light weight and compactness as to be conveniently carried in a coat pocket.

With the general object indicated in view, the invention consists in certain novel features of construction and organization of parts as herein-after described and claimed; and in order that it may be fully understood reference is to be had to the accompanying drawing, in which:—

Figure 1 is a perspective view of an alarm device embodying the invention.

Figure 2 is a top plan view of the same, broken away to disclose the spring element.

Figure 3 is an end view with a striker in impact position.

Figure 4 is a cross section on line IV—IV of Figure 1.

Figure 5 is a fragmentary vertical section to disclose the operative and detachable relation between the shaft to be turned by the spring and the locking key therefor for dislocation by a sufficient pull on the cord or following the release or cutting thereof.

Referring now to the detail construction of the device, a support preferably in the form of a sheet metal or equivalent housing, comprises an inverted U-shaped frame 1, having foot portions 2, a base 3 connected at its ends to and underlying the foot portions, and two sides 4 against opposite side edges of the frame 1 and the base 3, the sides having inturned marginal flanges 5 embracing the base and top portions and the vertical portions which constitute the ends of the housing, the parts being secured together as a unit by bolts 6 and nuts 7.

Extending through the housing and journaled in the ends thereof, is a shaft 8 provided at one of its extremities with a cross-head 9, and at the other end with a diametric notch 10, and at the end of the housing in proximity to said shaft notch, a cam 11 is provided for a purpose which hereinafter appears, the cam being in fixed relation to the housing. Any suitable or conventional method may be resorted to for preventing endwise

play or shifting of the shaft 8. As shown, it is embraced by a sectional shaft 12 for abutment against the inner sides of the ends of the housing, cotters 13, or the like, extending through shaft 8 and the sections of shaft 12 to secure the parts together as a unit. A spiral spring 14 fits around the shaft and at one end is secured to the latter or to the adjacent cotter. The opposite end of the spring is fastened to the housing in any suitable manner, but preferably by extending it up to and across the housing between the top thereof and the sides, and providing it with a hook terminal 15 for firm anchorage between the opposed parts of the top and abutting side of the housing.

A pair of similar equi-sized strikers or clappers 16, preferably of semi-disk form, are fitted against the outer side of and respectively pivoted at 17 to the shaft cross-head 9 near its opposite ends, the arrangement being such that each rotation of the shaft in the direction indicated by the arrow in Figure 3, shall cause the strikers to successively function, the arcuate edge of each, striking with considerable force because the power of the stroke, due to the speed of rotation, is augmented by that of centrifugal force, as each striker, not only travels around the axis of shaft 8, but swings around its respective pivotal point. The object struck by the strikers may be a bell, a pan, part of a bed frame, or any other resounding support, but for compactness, and to avoid marring finished woodwork, it is desirable to employ a resilient plate to receive the strokes of the striker. Such a plate 18, is shown fastened to and projecting laterally from the foot underlying the cross-head, it being apparent that immediately following impact of a striker, the latter, due to the uninterrupted rotation of the cross-head, swings upwardly on its pivot or in the reverse direction to its centrifugal travel, so that it shall slide or drag over and pass out of contact with the plate before the second striker engages the latter. The employment of a resilient plate slightly arched, guards against chance of the strikers locking, and insures a greater volume of sound, the sound effect being akin to that of a machine gun.

One of the pivots 17 is extended to serve as a crank handle for convenience in rotating the shaft to rewind the spring. When about fully rewound, and with the notch 10 facing upward, a key 19 is fitted at its lower end in the notch, the key having a shoulder 20 to rest upon the shaft back of the notch. A cord 21 is attached to the key and run to a door, window or the like

of the building or structure to be protected, the cord being under sufficient tension to prevent the spring, by unwinding action, from bringing the key against the cam 11. By arranging the 5 cord to hold the key in approximately vertical position, and the cord so that it cannot initially exert a pull endwise of the key, it will be obvious that a slight pull on the key caused by sagging of or wind pressure on the cord, will not with- 10 draw the key and result in sounding an alarm, but that any pull on the cord sufficient to turn the shaft against the resistance of the spring 12, enough to dispose the key in approximate end- 15 wise alignment with that portion of the cord running directly from the key, will result in the dislocation or withdrawal of the key from the notch and thus leave the spring free to revolve the shaft. It will also be apparent that the 20 breaking, cutting or detachment of the cord from the structure protected, will remove restraining force from the spring, and that immediately thereafter, it will cause the key to engage the cam and be forced outward thereby from the notch, thus leaving the spring free to revolve the 25 shaft and sound the alarm until the power of the former is spent. As in rewinding the spring the strikers drop as they pass dead center—their respective pivotal points—it is desirable that the plate 13 shall project beyond the op- 30 posite side of the housing from its arched or resonant end, and thus protect the surface of the supporting bed or the like, from injury by the strikers during the rewinding operation of the spring.

35 From the above description, it will be apparent that I have produced a construction embodying all of the features of advantage set forth as desirable and while I have described and illustrated the preferred construction, it is to be un- 40 derstood that I reserve the right to all changes within the spirit of the invention and without the ambit of the prior art.

I claim:—

1. In an alarm device, a support, a shaft journaled therein, means for rotating the shaft, a key detachably mounted on the shaft, a cord attached to the key for restraining the shaft from operation by said means, a striker rotatable with and pivotally connected to the shaft at a 45 point displaced with respect to the axis of the shaft, and means for effecting dislocation of the key relative to the shaft under rotation of the latter by the first-named means, when the shaft is free of restraint by the cord.
2. In an alarm device, a support, a shaft journaled therein, means for rotating the shaft, a key detachably mounted on the shaft, a cord attached to the key for restraining the shaft from operation by said means, a striker rotatable with 50 and pivotally connected to the shaft at a point displaced with respect to the axis of the shaft, and a cam in the path of rotation of the key by the said means, when the shaft is free of restraint by the cord.
3. In an alarm device, a support, a shaft journaled therein, means for rotating the shaft, a key detachably mounted on the shaft, a cord attached to the key for restraining the shaft from operation by said means, a striker rotatable with 55 and pivotally connected to the shaft at a point displaced with respect to the axis of the shaft, and a cam fixed with relation to the support and in the path of rotation of the key, when the shaft is free of restraint by the cord.
4. In an alarm device, a support, a shaft jour-

naled therein, means for turning the shaft in one direction, a striker rotatable with the shaft, a key detachably secured to the shaft, and a cord connected to the key eccentrically of the shaft and normally under tension to prevent operation 5 of the shaft by said means, and adapted when pulled with sufficient force, to apply pressure laterally on and turn the shaft in opposition to said means and then disengage the key from the shaft by causing endwise movement of the key 10 radially of the shaft.

5. In an alarm device, a support, a shaft journaled therein, means for turning the shaft in one direction, a pin eccentrically carried by the shaft and forming a handle for rotating the shaft 15 against the reaction of said turning means, a striker pivotally supported on said pin for swinging movement independently of rotation of the shaft, a key detachably secured to the shaft, and a cord connected to the key eccentrically of the shaft and normally under tension to prevent operation 20 of the shaft by said means, and adapted when pulled with sufficient force, to apply pressure laterally on and turn the shaft in opposition to said means and then disengage the key 25 from the shaft by causing endwise movement of the key radially of the shaft.

6. In an alarm device, a support, a shaft journaled therein, provided with a radial notch and a striker, means tending to revolve the shaft in one direction, a key standing upright on the shaft and engaging the notch thereof, and a cord connected to the key eccentrically of the shaft and normally under tension to prevent operation of the latter and adapted under sufficient increase 30 of tension, to apply pressure laterally on and turn the shaft in opposition to said means to effect endwise withdrawal of the key from said notch.

7. In an alarm device, a housing, a cam at one 40 end thereof, a shaft journaled in the housing and projecting through the ends thereof, a spiral spring surrounding the shaft and in fixed relation at its ends to the shaft and housing respectively, a key detachably carried by the shaft, a cord attached to the key and, when under tension, causing the latter to hold the shaft against rotation by said spring, the key, when relieved of restraint by the cord, being caused in turning with the shaft, to engage and be dislocated from 45 the shaft by said cam, and a striker rotatable with the shaft.

8. In an alarm device, a housing, a shaft journaled in and projecting beyond the ends of the housing, a spiral spring encircling the shaft within the housing and secured at its opposite ends respectively to the shaft and the housing, a cross-head on one end of the shaft, a pair of semi-circular strikers pivoted to the cross-head at opposite ends thereof and adapted for independent swinging movement relative to the cross-head, a key to engage and hold the shaft against operation by the said spring when under tension, means for first applying force laterally on the key to cause it to turn the shaft in opposition to the spring, and then endwise on the key to pull it out of engagement with the shaft, and means for tripping the key from the shaft when the latter is turned by the spring when freed for action by removal of the restraint of the means 55 for applying force laterally on the key.

9. In an alarm device, an alarm mechanism, a resiliently-actuated rotatable shaft to effect operation of the alarm mechanism, a flexible member constantly tensioned by the reaction of the 60

resiliently-actuated rotatable shaft and holding the shaft against rotation, and a key connecting the flexible member to the resiliently-actuated rotatable shaft and releasable on predetermined movement of the flexible member to free the resiliently-actuated shaft for rotation, said shaft being rotatable through at least an arc greater than 360°.

10. In an alarm device, an alarm mechanism, a resiliently actuated slotted rotatable shaft to effect operation of the alarm mechanism, a flexible member constantly tensioned by the reaction of the resiliently-actuated rotatable shaft and holding the shaft against rotation, and a key connecting the flexible member to the shaft by

being detachably received in the slot of said shaft, said key being withdrawn from the slot on predetermined movement of the flexible member and said shaft being rotatable through at least an arc greater than 360°.

11. In an alarm mechanism, a support, a shaft journaled therein, means applying a yielding force tending to revolve the shaft in one direction, a striker revolvable with and around the shaft and also bearing a pivotal relation thereto at a point offset relative to the axis of the shaft, and a flexible member normally restraining the shaft against movement but bearing a severable relation to the shaft to release same for operation.
